UNITED STATES PATENT OFFICE

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE

LOCK

Original application filed April 28, 1921, Serial No. 465,166. Divided and this application filed October 3, 1928, Serial No. 310,093. Renewed November 13, 1930.

This invention relates to certain new and useful improvements in locks suited for use in connection with automobile door handles, electrical switches and the like, and is a division, as to all subject matter, of my application for Letters Patent of the United States, filed April 28, 1921, Serial No. 465,166.

It is an object of this invention to provide an improved lock structure having a rotatable member for operating suitable mechanism, such as a door latch, switch or other means, which is held in one position against movement in either direction except by a key but may be moved in one direction from its position to the first position independently of the key.

Another object of this invention resides in the provision of an improved lock device wherein the usual locking tumblers ride on angular surfaces while being moved in one direction from unlocked position to locking position to permit the setting of the lock without the use of a key.

It is a further object of this invention to provide an improved lock structure having a cylinder mounting head and a tumbler carrying cylinder rotatable in the head and having disc or flat tumblers arranged to be pressed flush with the cylinder circumference upon its rotation from one position to a second position but adapted to hold the cylinder against rotation from the last position to the first position except by the retraction of the tumblers by the insertion of a proper key.

And a still further object of this invention resides in the provision of a lock of the character described in which the cylinder may be readily rotated to and from either locked or unlocked position by a proper key inserted therein or may be rotated independently of a key from one position only and being held against rotation from the other position except by use of the key.

With the above and other objects in view which will appear as the description proceeds, my invention resides in the novel construction, combination and arrangement of parts substantially as hereinafter described and more particularly defined by the appended claims, it being understood that such

changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a central sectional view of a handle lock as applied to an automobile door handle member and constructed in accordance with this invention;

Figure 2 is an end view thereof;

Figure 3 is a sectional view through the locking bolt;

Figure 4 is a sectional view through the tumbler cylinder;

Figure 5 is a sectional view through the twirler;

Figure 6 is a perspective view of the driver; and

Figure 7 is a detail view showing the driver pin in the lock bolt slot.

Referring now more particularly to the accompanying drawings, in which like numerals designate like parts throughout the several views, 10 designates an escutcheon adapted to be attached to an automobile door or other device in any suitable manner, as by means of screws 12 preferably entering from the inner side of the door. The escutcheon forms a bearing for a door handle member 13 the outer end portion of which provides a lock cylinder mounting head and the inner end of which has a square shank 14 extended therefrom for operating a suitable latch mechanism, not shown.

A locking bolt 15 passes transversely through the lock cylinder mounting head or member 13 and is projectable therefrom into engagement with a slot 16 in the escutcheon to restrain turning of the member to be locked. The movements of the locking bolt are controlled by a lock cylinder 17 rotatably mounted in the mounting head or member 13 and arranged to operate the locking bolt through a driver 18 the axis of which intersects that of the locking bolt. The driver and the lock bolt 15 are so related that turn-

ing movements of the former produces a reciprocation of the latter, this being accomplished by a pin 19 projecting from the end of the driver 18 slightly eccentric thereto 5 and fitting in a transverse slot 20 in the locking bolt. The slot 20 does not extend entirely across the locking bolt and its inner closed end forms a stop against which the pin 19 strikes to limit the rotary movement 10 of the driver to one-half of a turn.

The operative connection between the driver 18 and the lock cylinder 17 consists of a pair of lugs or projections 21 extending from the end of the driver and fitting with- 15 in a key slot 22 extended longitudinally through the lock cylinder.

A spring 22' seated in a pocket in the end of the driver 18 between the lugs 21 bears on the end of the lock cylinder and takes 20 up all play between the parts to prevent rattling, the driver 18 being thus held against the locking bolt 15 and the lock cylinder 17 against a retaining ring 23 which forms a bushing at the end of the handle member 25 through which the lock cylinder projects. A shoulder is formed on the lock cylinder to receive this end thrust by its engagement with the retaining ring.

A proper key 24, when entered through 30 the key slot 22, passes through openings 25' of a series of tumblers 25 fitting in transverse slots 26' of the lock cylinder and its opposite serrated edges cause the tumblers to be contained within the lock cylinder for rotation by the key to throw the locking bolt.

When the key is withdrawn, however, which may be in either the locking or un-locking position of the locking bolt, the tumblers are free to drop into the lowermost of 40 a pair of diametrically opposite grooves 26 within the handle member, and one of the tumblers, in the present instance the innermost one, is yieldably urged by a spring 29 to project one end beyond the periphery of 45 the lock cylinder and into one of the grooves. When the key is withdrawn with the locking bolt in the locking position, the tumblers projecting into the grooves 26 effectively prevent the lock cylinder from being turned 50 and, therefore, prevent the withdrawal of the locking bolt, and consequently the member being locked cannot be actuated.

When the grooves 26 are formed with parallel sides, as usual, the tumblers projecting 55 therein prevent the lock cylinder from being turned in either direction, irrespective of whether the locking bolt is in the locking position or unlocking position. As shown, however, the grooves have cam or angular 60 surfaces 27 on one side thereof, by the action of which the tumblers are forced into the lock cylinder when the latter is turned in one direction from one position.

The relation of the eccentric pin 19 and the slot of the locking bolt is such that the

lock cylinder may only have a half turn, and the cam action for returning the tumblers to the lock cylinder takes place only during the movement of the lock cylinder from the position in which the handle or other member is 70 unlocked to the position in which the member is locked. It will be apparent that on completing the half turn of the lock cylinder in this direction, the tumblers again enter the grooves 26, but as no further movement in 75 this direction is permitted by the engagement of the eccentric pin 19 with the end of the locking bolt slot, the cam surfaces 27 cannot be made to again withdraw the tumblers, and the lock cylinder is effectively locked against 80 movement in either direction.

This movement of the lock cylinder under which the cams act to return the tumblers may be effected without the presence of the key by turning the projecting end of the cylinder 85 by hand, but the member having been locked by this action can only be unlocked by inserting the proper key to withdraw the tumblers and then turning the key to withdraw the locking bolt. For convenience in turning 90 the projecting end of the lock cylinder by hand it may be provided with a serrated flange or twirler 28.

When the locking bolt is withdrawn, the handle or other member may be freely rotated to operate the latch in the usual manner and when it is desired to lock the door or other device, the lock cylinder may be rotated to locked position independently of the key, as before described. When locked, 100 however, the handle or other member cannot be moved until the locking bolt is withdrawn and this requires the use of the key.

It is obvious that the lock provided with hand operated means for rotating it to a 105 locking position while requiring a key to release it and return it to an unlocking position is not necessarily associated with a turning handle in order to have value, but it may possess many of the advantages of the invention 110 when otherwise arranged, as when the turning of the lock cylinder directly actuates a switch or other mechanism.

What I claim as my invention is:

1. In a lock, a lock cylinder mounting head 115 having a cylindrical bore, the wall of which is provided with diametrically opposed longitudinal slots, a lock cylinder mounted to turn in the bore of the mounting head, tumblers carried by the lock cylinder and normally urged to engage in the slots of the mounting head when in register therewith to restrain the cylinder against rotation in the mounting head, said tumblers being retractable within the circumference of the cylinder 120 by the insertion of a proper key to free the cylinder for rotation in the mounting head, and means operable upon rotation of the cylinder 125 in one direction to press the tumblers within the circumference of the cylinder. 130

2. In a lock, a lock cylinder mounting head having a cylindrical bore the wall of which is provided with diametrically opposed longitudinal slots, a lock cylinder mounted to turn in the bore of the mounting head, 5 tumblers carried by the lock cylinder and normally urged to engage in the slots of the mounting head when in register therewith to restrain the cylinder against rotation in the mounting head, said tumblers being retractable within the circumference of the cylinder by the insertion of a proper key to free the cylinder for rotation in the mounting head, means operable upon rotation of the cylinder 10 in one direction to press the tumblers within the circumference of the cylinder, and means limiting the rotation of the cylinder in the mounting head.

3. In a lock, a mounting member having a 20 bore, a lock cylinder movably mounted in the mounting member bore and having a key slot, abutments carried by the mounting member and communicating with the bore, locking tumblers carried by the lock cylinder, means 25 at all times yieldably urging at least one of the locking tumblers outwardly of the lock cylinder, said tumblers being engaged with one of the abutments when the lock cylinder is in one position to prevent movement thereof and being retractable out of engagement 30 with said abutment to free the lock cylinder for movement upon the insertion of a proper key in the key slot, and means independent of the key for pressing the tumblers and into the lock cylinder to free the same for movement 35 from its position engaging the tumblers with another of said abutments.

4. In a lock structure of the character described, the combination with a mounting 40 member, of a lock cylinder movable in the mounting member between locked and unlocked positions in the performance of its normal locking function, locking tumblers carried by the lock cylinder, means normally 45 yieldably urging at least one of said tumblers outwardly of the lock cylinder, and means carried by the mounting member and cooperating with said yieldably urged locking tumbler to positively prevent movement of 50 the lock cylinder when in locked position and yieldably restrain movement when in unlocked position.

In testimony whereof I have hereunto affixed my signature.

EDWARD N. JACOBI.
